BABY SHOE

Alice Carver, New York, N. Y., assignor to Richard G. Krueger, Inc., New York, N. Y., a corporation of New York

Application March 21, 1952, Serial No. 18,999

Term of patent 14 years

(Cl. D7—7)

To all whom it may concern:

Be it known that I, Alice Carver, a citizen of the United States of America and a resident of New York, in the county and State of New York, have invented a new, original, and ornamental Design for a Baby Shoe, of which the following is a specification, reference being had to the accompanying drawing, forming a part hereof, in which—

Fig. 1 is a side elevational view of a baby shoe, showing my new design.

Fig. 2 is a top plan view thereof.

Fig. 3 is a bottom view of the shoe.

Fig. 4 is a side perspective view of the shoe with the upper quarters in an opened position.

I claim:

The ornamental design for a baby shoe, as shown.

ALICE CARVER.
